G. F. VOIGHT

PLASTERER'S NAIL

Filed Sept. 22, 1921

FIG. 1.

FIG. 2.

FIG. 3.

FIG. 4.

INVENTOR

George F. Voight

UNITED STATES PATENT OFFICE.

GEORGE F. VOIGHT, OF OAKLAND, CALIFORNIA.

PLASTERER'S NAIL.

Application filed September 22, 1921. Serial No. 502,387.

To all whom it may concern:

Be it known that I, GEORGE F. VOIGHT, a citizen of the United States, residing at Oakland, in the county of Alameda and State of California, have invented new and useful Improvements in Plasterers' Nails, of which the following is a specification.

My invention relates to improvements in plasterers' nails adapted for securing and spacing wire netting on the wall sheathing of frame buildings preparatory to plastering; and an object of the invention is the provision of a nail for the purposes aforesaid, 10 formed of a single piece of metal and embodying a body portion comprising a driven or shank member provided at its upper end with an extension or upper jaw member, and a clamping or lower jaw member. The 15 connection between the clamping member and the body portion comprising a comparatively narrow section, which is intended to bend during the driving of the nail to permit the clamping member to move upwardly 20 for cooperation with the upper jaw for holding a netting wire therebetween.

With the foregoing and other objects and purposes in view which will appear as the description proceeds, my invention resides 25 in the combination and arrangement of parts and in the details of construction hereinafter described and claimed, it being understood that changes in the precise embodiment of the invention herein disclosed can 30 be made within the scope of what is claimed without departing from the spirit of the invention.

In the accompanying drawings—

Figure 1 is a side elevation of my invention, 40 showing the nail partly driven into a board with the lower portion of the lower jaw in engagement therewith and a portion of the wire netting disposed between the lower and upper jaws, the board and wire being shown in section.

Figure 2 is a front elevation of the nail as illustrated in Fig. 1.

Figure 3 is a side elevation of the nail, 50 showing the relative position of the lower jaw after the nail has been driven into the board as far as it is intended to go.

Figure 4 is a sectional view on line 4—4, Fig. 3.

Figure 5 is a view in perspective of a 55 modification in that the lower jaw is not

provided with the projection along one side of its lower edge.

Referring to the drawings in detail, throughout which like reference characters designate like parts—

The numeral 1 designates the shank of the nail, which is preferably a stamping from sheet metal, and has upon one side at its upper end an outwardly projecting upper jaw 2, and intermediate its ends a 60 lower jaw 3, which is disposed in the same plane as the upper jaw and has upon one side at its lower edge a shoe 4.

The arrangement of the jaws 2 and 3 being such as to form a slot 5 extending from 70 the outer extremities of the jaws inwardly to the shank 1, which slot operatively receives the wire 6 forming a portion of a plasterer's netting 7.

Upon the lower side of the jaw 3, adjacent the side of the shank 1, is an arcuated notch 8, thereby forming a reduced and operatively bendable portion 9 at the point of union of the jaw with the shank. (See 75 relative positions of the jaws in Figures 80 1 and 3).

The shoe 4 is intended to provide additional bearing surface for the clamping member 3, thereby preventing this member 85 from penetrating the sheathing boards when the nail is struck an excessive blow with the hammer in driving it thereinto.

In the modification of the invention, as shown in Fig. 5, the shoe 4 is omitted, in which case the lower edge of the clamping member 3 forms the bearing surface 90 adapted to engage the face of the sheathing boards. Such elimination of the shoe 4 may be readily carried out without impairing the functioning of the clamping member 95 as means for spacing and securing the netting wire, provided the metal from which the nail is formed is of sufficient thickness to provide the necessary bearing surface for the lower edge of the clamping 100 member.

In Figures 1 and 2 are shown the finished nail as manufactured, partly driven into a board 10, and in which construction the slot 5 is open to receive a strand of the wire 105 netting 7, while in Figures 3 and 4 is shown the nail after its final driving into the timber and the lower jaw bent up into engagement with the upper jaw 2 for permanently locking the wire in the slot, and at the same 110

time giving the wire a definite spacing from the timber necessary for the proper clinching of the plaster.

The upper edge of the extension 2 is preferably inclined downwardly towards its outer end, thereby preventing engagement therewith by the hammer when driving the nail. Any such engagement would be likely to result in the bending of the nail and thereby prevent proper operation of the clamping member 3 for the purposes set forth.

The lower edge of the clamping member 3 is also inclined downwardly towards its outer end, thereby providing for the engagement of said outer end with the sheathing boards prior to the engagement thereof by its inner or heel end, thus providing proper leverage for the bending of the connection 9.

I claim:

1. In a nail of the character described, in combination, a body portion comprising a shank member having an extension on one side at its upper end, a clamping member disposed below said extension, said extension and clamping member and shank disposed in the same plane, and a connection between said clamping member and said body portion, said connection having a notch cut in its lower side.

2. A nail for securing and spacing wire netting, comprising a shank member having a lateral projection on one side at its upper end and a clamping member spaced a distance below said projection, said shank member and lateral projection and clamping member being disposed in the same plane, the point of union of said clamping member with said shank member being substantially less in cross section along said plane than the width of the body portion of said clamping member along said plane, the arrangement being such that when said shank member is driven a proper distance in a support it will cause the free end of the clamping member to engage the support and said point of union to bend whereby said clamping member may be caused to coact with said projection for operatively locking the wire netting therebetween.

3. A plasterer's nail comprising, a shank member, an upper jaw member, a clamping member disposed below said upper jaw member, and a connection between said clamping member and one of said first named members, said connection having a notch formed in one side for reducing its dimensions in cross section thereby causing said connection to bend at said notch and said clamping member to move upwardly for cooperation with said upper jaw member for confining a netting wire therebetween, when the free end of said clamping

member is caused to engage the support into which the shank member is operatively driven a proper distance.

4. In a plasterer's nail, a shank member having an extension at its upper end, and a clamping member disposed below said extension, said members and extension unitarily joined together and disposed in the same plane, the upper face side of said extension inclined downwardly towards its outer end, the lower face of said clamping member normally inclined downwardly towards its outer extremity, the arrangement being such as to cause said outer extremity to engage the support into which the nail is driven and thereby cause a portion of said clamping member to bend and said clamping member to move upwardly into its permanent position for cooperation with said extension for holding a netting wire a distance outwardly from said support, in said permanent position said lower face of said clamping member being disposed in a plane substantially at right angles with the axis of the shank member.

5. In a plasterer's nail, a body portion comprising a shank member having an extension on one side at its upper end, a clamping member disposed below said extension, and an operatively bendable connection between said clamping member and said body portion, the lower face of said clamping member normally inclined downwardly towards its outer extremity for engagement adjacent said extremity with the support into which the nail is driven, for causing said connection to bend and said clamping member to move upwards relative to said body portion into its permanent position for cooperation with said extension for holding a netting wire a distance outwardly from said support, in said permanent position said lower face of the clamping member being changed from its downwardly inclined position to a position substantially parallel with the plane of said support.

6. A nail for securing and spacing wire netting, formed of a single piece of metal and embodying a shank member having an extension on one side at its upper end, the intersection of said extension with said shank member forming a crotch, and a clamping member disposed below said extension and having a projection adjacent its lower end adapted to engage the support into which said shank member may be driven, for bending said clamping member for engaging said wire netting and holding it in said crotch.

7. A plasterer's nail comprising, a shank member, an extension at the upper end thereof, and a clamping member disposed below said extension, said members and extension unitarily connected together and dis-

posed in the same plane, said clamping member having a notch at one end, the opposite end thereof adapted to engage a support for bending it at said notch for moving it relative to said shank for cooperation with said extension for binding a wire therebetween when said shank is driven in said support a proper distance, said clamping

member adapted to form means for limiting the penetration of said shank into said support when operatively driven thereinto. 10

In testimony of the foregoing being my own, I have hereunto affixed my signature this 17th day of September, 1921.

GEORGE F. VOIGHT.
